UNITED STATES PATENT OFFICE.

MAXIMILIAN K. GOLDEN, OF DETROIT, MICHIGAN, ASSIGNOR TO GOLDEN MANUFACTURING COMPANY, OF DETROIT, MICHIGAN, A CORPORATION OF MICHIGAN.

ELECTRIC LAUNDRY-IRON.

1,123,520.

Specification of Letters Patent.

Patented Jan. 5, 1915.

Application filed July 6, 1914. Serial No. 849,084.

To all whom it may concern:

Be it known that I, MAXIMILIAN K. GOLDEN, a citizen of the United States, residing at Detroit, county of Wayne, State 5 of Michigan, have invented a certain new and useful Improvement in Electric Laundry-Irons, and declare the following to be a full, clear, and exact description of the same, such as will enable others skilled in 10 the art to which it pertains to make and use the same, reference being had to the accompanying drawings, which form a part of this specification.

My invention relates to an electric laundry iron and its method of manufacture, shown in the accompanying drawings and more particularly pointed out in the following specification and claims.

As ordinarily constructed the body of a laundry iron is either a heavy casting, or is made up of a plurality of relatively heavy plates housed within its body portion, whereby the necessary weight required for effective service is provided. Such a construction is necessarily expensive both in regard to the material used, and the cost of assembling the parts.

The object of this invention is to produce a practical and efficient iron at a minimum cost of manufacture.

Other advantages and improvements will hereafter appear.

In the drawings accompanying this specification:—Figure 1, is a vertical longitudinal sectional view of the iron. Fig. 2, is a horizontal sectional view through the body of the iron. Fig. 3, is a cross sectional view of a detail of the heating element, shown on an enlarged scale—indicating the surrounding body of sand, and the insulating coating of glass or silica adjacent to the heating element formed from the sand in the process of manufacture.

Referring to the letters of reference placed upon the drawings:—A, denotes the body of the iron, formed of sheet metal; B, a closure wall at the enlarged end of the body of the iron which may be engaged to the body portion by over-lapping and interlocking the edges of the respective members as shown, or it may be secured in any other suitable manner.

C, indicates a wooden handle engaged to the body of the iron by a bail D.

E, denotes an electric heating element

which may be of any suitable form, that shown in the drawing being stamped out of flat metal connected by terminals E' with the usual flexible cord E², leading to a lamp socket (not shown) that connection may be made with an electric circuit.

F, is an insulating element projecting through the body of the iron and surrounding the terminals E'.

F' is a thimble to protect the end of the terminals and the connecting cord from injury.

H denotes a volume of sand lodged in the iron and embedding the heating element.

h, indicates an insulation of silica inclosing the heating element.

Having indicated the several parts by reference letters the construction of the device will be readily understood.

The parts being properly assembled with sand packed tightly around the heating element, the end wall B, is then secured in position and a current of a relatively higher voltage than would ordinarily be employed is directed to the heating element, which acting upon the adjacent sand forms a silica coating around the heating element which serves as an insulation. The necessary weight for effective service being supplied by a body of sand, which also provides an insulation for the heating element when acted upon by a relative strong electric current in the process of manufacture:—it will be obvious that the cost of production is materially reduced over that of electric irons in common use.

Having thus described my invention what I claim is:—

1. In a device of the character described, a body portion formed of sheet metal, an electric heating element located within the body portion, sand lodged within the body portion surrounding the heating element, the sand adjacent the heating element being fused, forming a silica insulation inclosing the heating element, and means for connecting the heating element with an electrical circuit.

2. In a device of the character described, a chambered body portion, an electric heating element located in the lower portion thereof and extending adjacent to and in parallel spaced relation from the bottom thereof, means for supplying an electric current to said heating element, said means

being disposed adjacent the upper side of the chambered body and extending therein, conductors connecting the heating element with the said means for supplying current thereto, sand disposed within and completely filling said chambered body portion, said sand completely surrounding the heating element and conductors, and the said sand adjacent the heating element being

fused, forming a silica insulation completely 10 inclosing the heating element and conductors.

In testimony whereof, I sign this specification in the presence of two witnesses.

MAXIMILIAN K. GOLDEN.
